UNITED STATES PATENT OFFICE.

HALBERT L. HALVERSON, OF WHITEWATER, WISCONSIN.

TAILOR'S CRAYON-SHARPENING MACHINE.

SPECIFICATION forming part of Letters Patent No. 372,315, dated November 1, 1887.

Application filed January 25, 1886. Serial No. 189,712. (Model.)

To all whom it may concern:

Be it known that I, HALBERT L. HALVERSON, a citizen of the United States, residing at the city of Whitewater, in the county of Walworth and State of Wisconsin, have invented 5 a new and useful Machine for Sharpening Tailors' Crayons, of which the following is a specification.

My invention relates to improvements in 10 machines for sharpening tailors' crayons; and the objects of my improvements are, first, to sharpen evenly both sides of the crayon at the same time; second, to afford facilities for adjusting the sharpening-knives; third, to remove and confine the dust. I attain these objects by the mechanism illustrated in the accompanying drawings, in which—

Figure 1 is a top view of the machine. Fig. 2 is a vertical section of the entire machine. 20 Fig. 3 is a vertical view of the knives in position for use. Fig. 4 is a side view of the machine. Fig. 5 is a vertical view of the machine on the line *a* in Fig. 1.

Similar letters refer to similar parts in the 25 several views.

The box *r*, with drawer *s*, constitutes the standard of the machine. At the top of the box *r*, and opening above the drawer *s*, is an opening corresponding to the hollow tube *k*. 30 The base or flange *g* of the cutter is connected to the box *r* by screws *e*. The hollow tube *k* receives the dust from the sharpened crayons through the holes or conducts *n* immediately beneath and in front of the knives *m*.

d is a triangular groove, from the inner surface of which project the cutting-knives *m*. The knives *m* rest in slots opening into the

groove *d*, and are adjusted by screws *c* behind them in the cutter-head, in which threads are cut to receive them. The knives *m* are 40 retained in position by the set-screws *b*.

The edges of the knives *m* are sharpened to correspond with the sides of the triangular groove *d*. The knives are inserted in the slots made for their reception, their edges adjusted, 45 as desired, beyond the plane of the sides of the groove *d* by means of the screws *c*, and then fastened into position by the set-screws *b*. The crayon is drawn against the edges of the knives *m*, guided and held in place by groove 50 *d*, and the dust drops of its own weight through the holes *n*, the tube *k*, into the drawer *s*.

The machine may be made of different parts and of any appropriate material, but preferably of brass cast in one piece. 55

I claim as my invention—

In a machine for sharpening tailors' crayons, the trough or chalk-guide having two or more knives or cutters protruding into said guide 60 from opposite sides, in combination with a post supporting said guide and cutters, said supporting-post having two or more holes or conducts passing down through its sides, one hole for each cutter, the upper portion of said 65 holes or conducts to be just in front of each cutter, and the lower end to terminate in orifices part way down the sides of the post to convey the cuttings from the cutters and prevent their being clogged.

HALBERT L. HALVERSON.
